ELECTROMAGNETIC RELAY

Alfred Gaebel and Hans-Fredi Schwartz, Berlin, Germany, assignors to C. Lorenz Aktiengesellschaft, Berlin-Tempelhof, Germany, a company

Application April 26, 1938, Serial No. 204,441
In Germany May 4, 1937

2 Claims. (Cl. 200—87)

The present invention relates to electromagnetic relays and more specifically to the type of relays which are adapted to operate in vacuum.

It is a well known expedient to place the contacts of an electromagnetic relay within a vacuum container in order to avoid operation troubles which may occur due to the oxidation of the contact elements and to secure high voltage contact make and break free of arcings. Devices of the type heretofore known involve the disadvantage that the various elements under voltage load are provided in relatively close proximity to one another. The switching at high voltages, therefore, causes flash-over from one element to other elements and particularly to such located externally with respect to the tube.

The invention has for its object to provide a vacuum relay which reliably operates at the highest voltages, in the order of 10,000 volts, for example. This is accomplished according to the invention by arranging the contact elements on an armature of insulation which also carries the magnetization responsive portion which is adapted to be influenced by the electromagnet or electromagnets of the vacuum relay. The corresponding magnet portions of old constructions are generally employed as conductors for the operating voltage so that flash-over from the interior to the exterior of the tube was not reliably prevented.

The invention will be more readily understood from the following description taken in conjunction with the accompanying drawing, in which:

Fig. 1 is a partially sectioned view of one embodiment of the invention; Fig. 2 illustrates a cross section along the line 2—2 of Fig. 1; while Fig. 3 is a further cross section along the line 3—3 of Fig. 1.

A vacuum container 2 of vitreous substance, for example, is attached by cementing to a socket 1 of ceramic material. This socket may serve as a handle when the vacuum relay is brought into any suitable support for attachment. Two rods 4 and 5 of insulation are sealed into the stem which is integral with the envelope or container 2. These rods serve as supports for the contacts and switching means of the vacuum relay. The upper end of the longer rod 4 carries a clip or clamp 6 to which a movable armature unit 7 is hinged. In the form shown the armature unit includes a flat strip 9 of insulation, e. g. ceramic material, a hinge member 8 movably attached to the clip or clamp 6, and magnetization responsive members 10 which are

adapted to be influenced by the electromagnets 16. The contact elements 11 effecting the opening and the closing of the operating circuits in co-operation with the fixed contact points 14 and 15 are arranged at the lower end of the armature unit. The current is applied to the device partly over the lead-in conductor 12 sealed to one end of the vacuum container and associated with the fixed contact element 14, and partly over the wires 13 which are carried through the stem. One of these last mentioned wires is connected to the movable contact element 11 while the other leads to the fixed contact element 15. The members 10 of the armature structure are arc-shaped so as to leave a narrow space only between these members and the cores of the electromagnets 16 of the relay. Since these members 10 are not connected to any electric load, any possibility for flash-over to the electromagnets through the wall of the envelope or container is reliably avoided. The shape of the contact elements, moreover, permits the make and break of a plurality of circuits.

In operation magnetic fields produced by electromagnets 16 act on the magnetization responsive members 10 and move the armature towards points 14 or 15 depending on the magnet energized or polarity of energization thus completing external circuits which may be connected to lead-in conductors 12 and 13. The electromagnets 16 may be energized by any suitable source.

What is claimed is:

1. In an electromagnetic relay, an evacuated envelope, a stem forming part of said envelope, a relatively long and a relatively short rod of insulating material embedded in said stem and projecting therefrom, a flat strip of insulating material hingedly supported on the free end of the long rod, the free end of the flat strip being adjacent the free end of the short insulating rod, contacts carried by the flat strip near its end, contacts carried by the two rods cooperating with the contacts on the flat strip, lead-in wires extending through the stem to the contacts on said flat strip and on the short insulating rod, a lead-in wire extending through another portion of the envelope to the contact on the relatively long rod, arcuate iron plates conforming to the walls in the envelope fastened to said flat strip intermediate its ends, and electromagnets outside of said envelope in alignment with said iron plates.
2. An electromagnetic relay comprising an evacuated envelope, a support within said envelope and attached thereto, an armature unit including a strip of insulating material, contacts

attached to said strip, and magnetization responsive members attached to said strip and insulated from said contacts, means for hinging said armature unit to said support, pole pieces outside said envelope in proximity to said magnetization responsive members, contacts fixedly attached to said envelope and cooperating with

said armature unit contacts, and lead-in conductors connected to said contacts, whereby flash-over to said pole pieces via said magnetization responsive members is avoided.
